UNITED STATES PATENT OFFICE

WILLIAM L. DE REMER, OF CHICAGO, ILLINOIS.

TIE-PLATE.

No. 853,683.

Specification of Letters Patent.

Patented May 14, 1907.

Application filed August 25, 1906. Serial No. 332,053

To all whom it may concern:

Be it known that I, WILLIAM L. DE REMER, a citizen of the United States, residing in Chicago, in the county of Cook, State of Illinois, have invented certain new and useful Improvements in Tie-Plates, of which the following is a specification.

My invention relates to that class of tie-plates having strengthening rail supporting ribs and adapted to be secured to railway ties for supporting and securing track rails in position.

The principal object of the invention is to provide a simple, economical and efficient tie-plate.

A further object is to provide a tie-plate of minimum weight and maximum effectual strength, having ribs adapted to support the rail and strengthen the plate longitudinally without requiring the use of longitudinal bottom flanges extending beneath the main load bearing bottom surface portion of the plate and which cut into the fibers of the tie.

A further object is to provide a tie-plate having ribs on its upper side which engage the rail to be supported and having ribs on its under side adapted to provide a load supporting bottom surface of greater area than the upper rail engaging surface portion of the plate, and to provide connecting portions of maximum strength and minimum weight between such main load supporting ribbed portions of the plate, whereby a plate of maximum strength and formed of the minimum amount of metal consistent with the required strength and having a load supporting bottom surface of large area is afforded.

Other and further objects of the invention will appear from an examination of the drawings and the following description and claims.

The invention consists of the features, combinations and details of construction herein-after described and claimed.

In the accompanying drawings Figure 1 is a plan view of a tie-plate constructed in accordance with my improvements; Fig. 2. A side elevation of the same, showing a track rail mounted thereon, and Fig. 3. A transverse sectional elevation taken on line "3" Fig. 1, looking in the direction of the arrow.

In constructing a tie-plate in accordance with my improvements I provide a main body portion *a* formed preferably of rolled metal of sufficient length to extend beneath

and transversely beyond the opposite sides 55 of the track rail to be supported thereby. The plate is provided with perforations *b* and *c*, arranged at suitable intervals on opposite sides of the rail engaging portion and in position to receive the spikes for holding the rail 60 and plate in position upon the tie. A rail retaining shoulder *d* extends transversely across the upper side of the plate in position to engage the outer edge of the bottom flange of a track rail so as to resist the side thrusts upon 65 the rail and retain it in position. The outer spike holes *b* extend through this shoulder and are reinforced thereby. The upper face of the plate is provided with a series of flat topped ribs *e* and a series of convex or round 70 topped ribs *f* which extend obliquely and at an acute angle with relation to the longitudinal center or length of the plate. These flat and round topped ribs are arranged in alternate relation and may extend from the rail 75 retaining shoulder or transverse rib inward longitudinally of the plate entirely across its rail engaging upper face portion.

The portions of the plate formed by the round topped ribs or arched portions *e* have 80 grooves *g* extending centrally thereof along the under side of the plate. These grooves are preferably of sufficient depth so that the arched portions are thinner than the portions of the plate between such arched portions. 85

In order to obtain the strongest construction or maximum rigidity coupled with minimum weight and quantity of material, the top of the arches or round topped rib portions should be flush with the top faces or 90 relatively flat rib portions. Bottom ribs *h* on the under side of the plate extend directly beneath and parallel with the upper ribs *e*, and each of these bottom rib portions forms a load bearing flat bottom surface portion of 95 greater area than the upper face of the rib beneath which such bottom rib extends. By this arrangement it will be seen that a plate containing the minimum amount of metal and having the maximum rigidity and strength is provided, and that the bottom ribs provide a large load bearing surface of much greater area than that of the rail engaging surface portions of the upper ribs beneath which such bottom ribs extend. The 100 bases of the arches formed by the intermediate round topped ribs or arched portions of the plate rest upon the flat faced rib portions. 105

and form connections there-between. Being arch shaped these round topped rib portions may be made of the lightest possible construction consistent with the strength required for resisting the stresses and strains to which such plates are subjected in use.

It is very desirable to avoid the use of sharp angles in the depressed portions of a plate formed of rolled metal, thus minimizing the 10 wearing away of the correspondingly projecting portions of the rolls which form such depressions or recesses. It is also desirable to enable the minimum amount of metal to be employed in the formation of the upper 15 rib portions which engage the rail to be supported. The side faces *i* of the relatively flat topped upper ribs *e* are therefore made concave so that they converge with the rounded faces of the round topped ribs in 20 such a manner that sharp edges are not required upon the rolls for forming such side faces or the recesses between the alternate round and flat topped upper ribs. The bottom grooves are also preferably rounded, 25 and, extending as they do obliquely at an acute angle with relation to the longitudinal center of the plate, the broad bottomed lower rib portions afford substantially all of the advantages of a flat bottom plate so far 30 as a large surface area is concerned.

The relatively broad bottom faces of the lower ribs prevent injury to the fibers of the tie and form a support for both the flat topped ribs and the arches or round topped 35 rib portions there-between and the load supported thereby.

By so constructing the plate that the ribs extend obliquely and at an acute angle with relation to the longitudinal center of the 40 plate—such longitudinal center extending transversely of the rail to be supported thereby—and by so disposing the arches that they alternate with the main load bearing ribs and extend obliquely with relation to the 45 longitudinal center of the plate, great longitudinal rigidity and sufficient transverse rigidity is afforded and the minimum amount of metal is required while at the same time the necessity for the use of depending longitudinal strengthening flanges which would 50 cut into the fibers of the tie is dispensed with.

I claim:

1. A tie-plate having on its upper side a transverse shoulder and ribs extending obliquely with the relation to such shoulder.

2. A tie-plate having on its upper side a transverse shoulder and a series of ribs extending obliquely and at an acute angle with relation to the longitudinal center of the 60 plate.

3. A tie-plate having on its upper side a series of substantially flat topped ribs extending at an acute angle with relation to its longitudinal center.

4. A tie-plate having on its upper side a transversely extending shoulder and alternate flat and round topped ribs extending obliquely with relation to the longitudinal center of the plate.

5. A tie-plate having a main body portion 70 provided with alternate flat and round topped ribs on its upper side.

6. A tie-plate formed of rolled metal having alternate flat and round topped ribs extending obliquely with relation to the longitudinal center of the plate.

7. A tie-plate having a main body portion provided with a series of ribs on its under side and having ribs on its upper side arranged directly over such bottom ribs and so connected by intermediate arched portions of the plate.

8. A tie-plate having a main body portion provided on its upper side with a series of rail supporting ribs, and having on its under side a series of ribs each having a bottom surface of greater area than the top surface of the upper rib beneath which such lower rib extends.

9. A tie-plate having on its upper side a series of ribs extending obliquely with relation to its longitudinal center, and having on its under side a series of bottom ribs each directly beneath one of such upper ribs and having a surface of greater area than the upper rib beneath which such lower rib extends.

10. A tie-plate having a main body portion provided with a series of ribs on its under side, and having on its upper side alternate relatively flat and rounded ribs, the relatively flat upper ribs being directly over the bottom ribs and connected by the rounded rib portions of the plate.

11. A tie-plate having a main body portion 105 provided with ribs forming substantially flat top and bottom surface portions, and having relatively thin arched portions integral with and forming connection between such rib portions of the plate.

12. A tie-plate having on its upper side a transversely extending shoulder and ribs extending at an acute angle with relation to the longitudinal center of the plate and transversely with relation to the rail to be supported thereby, and having on its under side a series of depending ribs each forming a load bearing bottom surface portion of greater area than the top surface of the ribs directly over such bottom ribs.

13. A tie-plate having a main body portion provided on its upper side with ribs having concave side faces and with ribs having rounded upper surface portions intermediate such concave sided ribs.

14. A tie-plate having a main body portion provided with ribs in oblique relation to its longitudinal center and having round topped

arch portions between and connecting such oblique rib portions.

15. A tie-plate having a main body portion provided with ribs, having substantially flat surface portions, and having relatively thin arched connecting portions between such ribs, the tops of the arched portions being on

the same plane with the top surfaces of the flat ribs.
